EYE PROTECTOR

Fred G. Gay, Jr., Greece, and Donald J. McCulloch, Rochester, N. Y., assignors to Bausch & Lomb Optical Company, Rochester, N. Y., a corporation of New York

Application December 15, 1951, Serial No. 17,748

Term of patent 14 years

(Cl. D57—1)

To all whom it may concern:

Be it known that we, Fred G. Gay, Jr., and Donald J. McCulloch, citizens of the United States and residents, respectively, of the town of Greece and Rochester, county of Monroe, and State of New York, have invented a new, original, and ornamental Design for Eye Protector, of which the following is a specification, reference being had to the accompanying drawing, forming a part hereof.

Fig. 1 is a front elevational view of an eye protector showing our new design.

Fig. 2 is a rear perspective view thereof.

Fig. 3 is a top plan view thereof with temples fragmentarily shown in dotted lines.

Fig. 4 is a side view thereof.

The essential features of our design are shown in full lines in the drawing.

We claim:

The ornamental design for an eye protector, substantially as shown and described.

FRED G. GAY, JR.
DONALD J. McCULLOCH.
